(57) **CLAIM**

The ornamental design for a portable power station, as shown and described.

DESCRIPTION

FIG. 1 is a perspective view of a portable power station showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof.

FIG. 9 is a partial enlarged view of FIG. 2; and,

FIG. 10 is a view of a portable power station in use.

The broken lines in the drawings illustrate the portions of the portable power station, which form no part of the claimed design. The dot-dash broken lines in FIG. 2 represent the boundary of the enlarged portion and form no part of the claimed design.
